US0D1074761S

(12) **United States Design Patent** (10) Patent No.: **US D1,074,761 S**
(45) Date of Patent: ** May 13, 2025

(54) **PRINTER OF EDIBLE IMAGES ON FLOWABLE MATTER**

(71) Applicant: **Ripples Ltd.**, Petah Tikva (IL)

(72) Inventors: **Eyal Eliav**, Tel Aviv (IL); **Guy Dvir**, Givataim (IL); **Roy Elitzur**, Or Akiva (IL); **Avner Sadot**, Tel Aviv (IL); **Mor Michael Brot**, Petah Tikva (IL)

(73) Assignee: **Ripples Ltd.**, Petach Tikva (IL)

(**) Term: **15 Years**

(21) Appl. No.: **29/770,943**

(22) Filed: **Feb. 18, 2021**

(51) LOC (15) Cl. **15-09**

(52) U.S. Cl.

USPC **D15/122**

(57) **CLAIM**

The ornamental design for a printer of edible images on flowable matter as shown and described.

DESCRIPTION

FIG. 1 is a front perspective view of a printer of edible images on flowable matter showing our new design;

FIG. 2 is a front plan view thereof;

FIG. 3 is a rear plan view thereof;

FIG. 4 is a left plan view thereof.

FIG. 5 is a right plan view thereof;

FIG. 6 is a top plan view thereof; and,

FIG. 7 is a bottom plan view thereof.

The broken lines in the drawing views represent portions of the printer of edible images on flowable matter that form no part of the claimed design.

1 Claim, 6 Drawing Sheets
